UNITED STATES PATENT OFFICE.

HIRAM B. NICKERSON, OF ORLEANS, MASSACHUSETTS.

MECHANICAL MUSICAL INSTRUMENT.

SPECIFICATION forming part of Letters Patent No. 243,720, dated July 5, 1881.

Application filed October 22, 1880. (No model.)

To all whom it may concern:

Be it known that I, HIRAM B. NICKERSON, of Orleans, in the county of Barnstable and State of Massachusetts, have invented a new 5 and useful Musical Instrument, of which the following is a specification.

My invention relates to that class of musical instruments in which perforated or embossed paper is used for opening the proper 10 valves at the times required for producing musical effects. The motive power may be supplied from any requisite source.

My invention consists in the arrangement 15 of valves and levers combined with grooved rollers and prepared paper, and in minor details, all of which may be best understood by reference to the specification and drawings.

In the drawings, Figure 1 is a plan of my invention. Fig. 2 is a longitudinal vertical section of the same. Fig. 3 shows portions of the 20 grooved feeding-rolls, and also the position of the ends of the operating-levers. Fig. 4 is a side elevation of the instrument. Fig. 5 is a cross vertical section of the same.

Let A represent the main casing of the instrument, and B the table or top of the instrument. Within the case, and immediately below the top B, I place the bellows D D', one 25 of which is shown in Fig. 2 and both in Fig. 5. These bellows D and D' are worked exhaustively by the working-beam F, which is hung at F', Fig. 5, and is worked by the pinion H and crank-pin h, the crank-pin h being inserted in the pinion H'.

F² and F³ are links for connecting the working-beam with the bellows D D'.

By operating the bellows D D' by the pinion H', I am enabled to exhaust very rapidly, as the same pinion H' makes a number of revolutions for each turn of the crank K and gear-wheel H². Thus the bellows are operated a number of times for each turn of the crank. Each of the bellows D D' is provided with an escape-valve, d, and a suction-valve, d', (see 40 Fig. 2,) and also an eduction-passage, P P P, to the wind-chamber E. This wind-chamber E is provided with a tension-spring, S, which tends to extend it to its full capacity. The effect of working the bellows D D' is to exhaust 45 the air from the wind-chamber E, and thus cause a flow of air through the reeds or pipes

of the instrument. The object of the wind-chamber and its springs is to give an even flow to the current of air through the reeds.

The blocks C' C', Figs. 1 and 2, are affixed 55 to the top B of the instrument, and serve as holders for the sounding-board L L. This sounding-board contains the reeds, one of which is shown at R, Fig. 2.

Immediately above each of the reeds R an 60 opening is made for the admission of a current of air to sound the notes, each one of these openings being provided with a valve, N, Figs. 1 and 2, each valve having a slight spring, v, to compress it when it is not acted upon by 65 the lever N' n. The lever N' n has under it a spring, n', Fig. 2, which forces it onto the end of the valve N, and thus will hold the valve open in opposition to the action of the spring v. This lever N' is pivoted at N². When its 70 end n is up, as indicated at Fig. 2, then its opposite end, N', rests on the rear part of the valve N and keeps it open, so that the corresponding note will be sounded.

The rolls M' M are grooved as indicated, corresponding grooves being set opposite to each other, as shown in Fig. 3, so as to allow room for movement of the end n of the lever N' n.

It is to be understood, of course, that the 80 number of the reeds, valves, levers, and grooves shall correspond with each other.

T, Fig. 2, represents one of a series of small bells, which may be inserted in the sounding-board, where they will modify the sound by ringing in unison or accord with the sound 85 given out by the reeds; or they may be sounded by small hammers attached to the rear end of the valve N. (See Fig. 2.)

The operation of the instrument is as follows: The perforated paper is inserted between 90 the feeding-rolls M M', and may be connected to the drawing-roll R', Figs. 1 and 2, by means of a hook, R², and clip R³, the clip R³ being attached to the roll R', as shown in Figs. 1 and 2, the roll R' being operated by a belt on 95 any convenient device. Now, if we suppose the paper which is inserted between the rollers M M' has no perforations, then the ends n of the levers N' n will be depressed. This action will raise the end n of the levers and allow 100 the valves N to close. This will prevent any current of air through the reeds, and no sound

will be produced. When the paper passes along, as it will when the crank K is turned, the perforations will present themselves and the end *n* of the corresponding lever will spring 5 up. This action will open the valve N, and its corresponding reed will sound.

The part L L, which contains the reeds R and the bells T, may be called the "resounding-board," as it is connected directly with the 10 primary sounding-board B B, the joint between the two being made air-tight by a soft packing, T'. The object of this resounding-board is to make the tones richer and not so shrill.

Having thus described my invention, what 15 I desire to secure by Letters Patent is—

1. In combination, the grooved feeding-rolls M M', drawing-roll R', levers N' *n* with their springs *n'* thereunder, valves N, with their

springs *v*, and the resounding-board L L, having reeds and openings, arranged to operate 20 substantially as described.

2. In a mechanical musical instrument, the drawing-roll R', with its clip R³, in combination with the hook R², for attaching the perforated paper thereto, as set forth. 25

3. The exhaust-bellows D D', with their links F² F³ under them, in combination with the working-beam F, located under the bellows and pivoted to the upright F', the pitman H, and crank-pinion H', all constructed and arranged 30 to operate as described.

HIRAM B. NICKERSON.
